UNITED STATES PATENT OFFICE

103,363

DESIGN FOR AN ELECTRIC LAMP SUPPORT

Eugene Schwarz, Alexandria, Ind., assignor to
The Mantle Lamp Company of America, Chicago, Ill., a corporation of Illinois

Application November 27, 1936, Serial No. 66,167

Term of patent 14 years

To all whom it may concern:

Be it known that I, Eugene Schwarz, a citizen of the United States of America, residing at Alexandria, in the county of Madison and State of Indiana, have invented a new, original, and ornamental Design for Electric Lamp Supports, of which the following is a specification, reference being had to the accompanying drawing, forming a part thereof.

The figure is a perspective view of an electric lamp support, showing my new design.

The side of the lamp support not shown in the drawing is of substantially the same appearance in reverse, as that shown in the drawing.

I claim:

The ornamental design for an electric lamp support, substantially as shown and described.

EUGENE SCHWARZ.
